Primary Examiner — Austin Murphy

(57) **CLAIM**

The ornamental design for a hand assembled, planar cubesat kit secured with 3D printed plug and play electromechanical connectors, as shown.

DESCRIPTION

FIG. 1 is a perspective view of the hand assembled, planar cubesat kit secured with 3D printed plug and play showing my new design;

FIG. 2 is a side view thereof, all other side views are identical; and,

FIG. 3 is a top view thereof, the bottom view is identical.
